UNITED STATES PATENT OFFICE.

PAUL GIFFARD, OF PARIS, FRANCE, ASSIGNOR TO CHARLES JAMES
ADOLPH DICK, OF PITTSBURG, PENNSYLVANIA.

IMPROVEMENT IN PACKINGS FOR PISTONS AND STOP-VALVES.

Specification forming part of Letters Patent No. 138,633, dated May 6, 1873; application filed
February 17, 1873.

To all whom it may concern:

Be it known that I, PAUL GIFFARD, of the city of Paris, in the republic of France, have invented certain Improvements in Pistons, of which the following is a specification:

The object of my invention is to improve the piston for which Letters Patent No. 122,825 were granted to me on the 16th day of January, 1872; and this object I attain by making the ring, which forms a prominent feature in the said patent, of hard material at its outer circumference where it bears against the cylinder, and of softer material at its inner circumference, the compressed fluids in the cylinder acting instantaneously on the soft material composing the inner part of the ring so as to insure at once a perfectly tight joint between the said ring and the plate against which it temporarily bears, while the harder outer portion of the ring which bears against the cylinder has the effect of reducing the friction to a minimum.

It will be unnecessary to explain here the operation of the ring during the reciprocating movement of the piston, as this is fully set forth in my aforesaid patent. The ring may be made of different materials—compressed paper or paste-board, for instance; but I prefer to make it of vulcanized rubber, as I am enabled to regulate or graduate the vulcanization so that the exterior of the ring may have the desired hardness and the inner portion the requisite softness.

When the ring has to be applied to a single-acting pump, I prefer to make it in the manner shown in Figure 1 of the accompanying drawing—that is, with two annular beads or ribs, *a a*, on its upper surface for bearing on the upper side of the piston's groove; or these annular ribs may be made on the piston and project into the groove of the same, the ring being flat, as shown in Fig. 2. In either case

the annular beads or ribs will facilitate the rapid completion of the joint on operating the piston.

For double-acting pumps the ring should have annular beads on both sides, as shown in Fig. 3; or both sides of the groove should have beads, the ring being flat. In some cases there may be but one bead, either on one side of the groove, as in Fig. 4, or on one side of the ring, for a single-acting pump; and for a double-acting pump there may be but one bead on each side of the piston's groove, as in Fig. 5, or on each side of the ring.

My improved piston may be applied with the best results to all double and single acting pumps for hydraulic purposes, as well as to air-pumps, exhaust or vacuum pumps, blast-engines, hydraulic presses, syringes, &c. It may also be applied to stop-valves in a manner substantially as shown in Fig. 6, which will be readily understood without explanation.

I claim as my invention, and as an improvement in the pump-piston for which Letters Patent were granted to me on the 16th day of January, 1872—

1. The within-described piston-ring, made softer at the inner than at the outer circumference, and adapted to the groove of a piston, all substantially as and for the purpose herein set forth.

2. The combination of a recessed piston, a packing-ring, and one or more annular bearings, *a a*, arranged to limit the play of the ring, substantially as described.

In testimony whereof I have signed my name to this specification in the presence of two subscribing witnesses.

PAUL GIFFARD.
